UNITED STATES PATENT OFFICE.

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

LAMP-SOCKET CASING.

1,103,678.

Specification of Letters Patent. Patented Aug. 25, 1914.

Application filed March 1, 1912. Serial No. 681,003.

To all whom it may concern:

Be it known that I, REUBEN B. BENJAMIN, a citizen of the United States, residing at Chicago, in the county of Cook and State of Illinois, have invented new and useful improvements in Lamp-Socket Casings, of which the following is a full, clear, concise, and exact description, reference being had to the accompanying drawing, forming a part of this specification.

My invention relates to lamp socket casings, and especially pertains to the means for securing the cap and the shell together.

As is well known, the casing of an electric lamp socket usually consists of a shell which contains the contact and binding terminal supporting base, and a cap which is removably secured to the shell and serves to protect the binding terminals and complete the casing. Difficulty has been experienced in producing a means for securing the cap to the shell, which will be sufficiently inexpensive to meet the commercial conditions, and which, at the same time, will be efficient and safe in use and convenient to handle when it is desired to assemble or take apart the casing.

With these conditions in view, therefore, it is the object of my invention to improve upon lamp socket casings in so far as the means for securing the cap to the shell is concerned.

Three forms of socket casing, each of which embodies the main features of my invention, are described, by way of example in the following specification, and shown in the accompanying drawings, in which:

Figure 1 is a side elevation of a socket casing constructed in accordance with my invention; Fig. 2 is a longitudinal section through the same; Fig. 3 is a sectional plan, the section being taken on the line 3—3 of Fig. 2, looking in the direction of the arrows; Fig. 4 is a fragmentary view of part of the shell; Fig. 5 is a detail view of the latch; Fig. 6 is a plan of the shell of a modified form of socket casing constructed in accordance with my invention, the cap being removed; Fig. 7 is a sectional elevation of the same with the cap in place, the section being taken on the line 7—7 of Fig. 6; Fig. 8 is a side elevation of the shell shown in Fig. 6; Fig. 9 is a plan of the shell of another modified form of socket casing constructed in accordance with my invention;

Fig. 10 is a side elevation of the same; and Fig. 11 is a section on the line 11—11 of Fig. 9, looking in the direction of the arrows, the cap being shown in place on the shell.

Referring first to Figs. 1—5 of the drawings: 10 designates the shell of the casing, and 11 designates the cap. The shell 10 is provided with two diametrically opposed latches 12, each of which consists of a vertically arranged resilient metallic strip riveted at its lower end, to the shell, within the same. The upper ends of these latches are bent outward to form tongues 13, which enter correspondingly shaped slots 14 formed in the shell 10 somewhat below the top edge thereof. The normal position of the latches 12 is that in which the tongues 13 do not extend through the slots 14 to an extent sufficient for them to project beyond the outer surface of the shell 10; but the tongues may be moved outward so that their ends project beyond the outer surface of the shell. This is effected by means of screws 15, which pass loosely through the shell and are threaded into the latches 12, these screws being located a little below the tongues 13. It will be seen that, by tightening the screws 15, the tongues 13 may be made to project outward beyond the surface of the shell. These tongues serve to secure the cap 11 in position. The cap 11 telescopes upon the shell 10, in the ordinary manner, and is formed with an inwardly concave annular bead 16, located so that it will be in alignment with the tongues 13 when the cap is in position upon the shell 10. The cap is extended down beyond the bead 16 so as to form an annular flange 17, of such depth that its lower edge will lie adjacent the screws 15, so that the flange 17 will be clamped beneath the heads of these screws, when they are tightened.

The device is used as follows, supposing the cap to be apart from the shell and the screws 15 to be loosened: The screws 15 being loose, the cap 11 may be readily placed upon the shell, so that the bead 16 will lie over the tongues 13, and the flange 17 will lie beneath the heads of the screws 15. With the cap 11 in this position, if the screws 15 be tightened, the result will be that the latches 12 will be pulled outward until the tongues 13 engage in the bead 16, and the flange 17 is securely clamped between the shell and the heads of the screws 15. When 110

the screws have been thus tightened the tongues 13, by reason of their engagement in the bead 16, will effectually prevent withdrawal of the cap. It will be seen that inward springing of the shell wall, which otherwise might result in the tongues 13 coming out of the recess 16, is prevented by the clamping action of the screws 15.

The manner of using the device has been described, for convenience, as though the cap were placed upon the socket; whereas, of course, in actual practice, the cap will usually be secured to a fixture, and it will be necessary to thrust the socket up into the cap, rather than to place the cap over the socket. Particularly in the case of switch sockets, it is of advantage that the casing be constructed so that the switch operating means may be made to extend in any desired direction. This advantage is obtained by means of my invention, since the shell 10 may be inserted in any desired angular position with relation to the cap 11, and becomes secured in such position when the screws 15 are tightened. The casing, with the cap securing means of my invention, is of simple and durable construction and may be economically produced.

The modified form of casing shown in Figs. 6, 7 and 8, differs from the form shown in Figs. 1-5, in that one of the latches 12 is dispensed with, a pair of outwardly-punched projections 18 being employed instead, on the side of the shell opposite that which bears the single latch which is used. The projections 18 are formed so as to present beveled surfaces at their upper parts and square surfaces—in the form shown, cut edges—at their lower parts. In assembling the casing, the shell may be thrust up into the cap, the projections 18 being enabled, by virtue of their beveled upper surfaces, to snap into the bead 16. The screw 15 is then tightened up, so as to pull the tongue 13 into the bead 16 and clamp the flange 17 against the shell, in the manner described above. When the shell is to be removed from the cap, the screw 15 is loosened, whereupon the shell may be released by a kind of tilting action, the part adjacent the latch 12 coming away from the cap first. This form of my invention has the advantages set out in connection with the form previously described. In the case of switch sockets, the projections 18 are preferably positioned away from the slot through which the switch operating member emerges from the casing. This being the case, it would not be possible to cause the metal of the shell to spring inwardly to an extent sufficient to permit the projections 18 to become disengaged from within the bead 16.

In the form of my invention shown in Figs. 9, 10 and 11, a strip 19 is employed.

This strip is similar in nature, and manner of being affixed, to the latches 12 described above, but it has no outwardly projecting tongue. The strip is placed adjacent the key slot 20 of the shell, and carries a screw 21, similar to the screws used in the modifications described above. Coöperating with the strip 19 and its clamping screw 21, is a projection 22 of a nature similar to that of the projections 18 of the form of shell described with reference to Figs. 6-8, the projection 22 being, however, placed close to the key slot 20. In addition to the projection 22, a pair of similar projections 23, placed on the side of the shell opposite to the projection 22, are provided. The cap is of the same construction as that described in dealing with the forms shown in the previous figures. The screws 21 being loosened, the casing may be assembled by merely pushing the shell up into the cap, the projections 22, 23, 23 snapping into the bead 16. The screw 21 is then tightened, the flange 17 of the cap being thus clamped between the shell and the head of the screw, and it being thus rendered impossible to cause the position of the shell adjacent the key slot 20 to spring inward and thus release the projection 22 from its engagement within the bead 16 of the shell. When the shell is to be removed from the cap, the screw 21 is loosened, whereupon, by thumb pressure or otherwise, the metal of the shell may be caused to spring inward and thus release the projection 22 from its engagement within the bead 16. The shell may then be removed from the cap by a kind of tilting action, the side which carries the projection 22 coming away first. This form of my invention also has the advantages set forth in connection with the other forms, described above.

While I have described and shown three of the constructions in which my invention may be embodied, these are not the only embodiments of the invention, which may take other forms than those described and shown,—what I claim being:

1. In a socket casing, the combination with a cap having an internal shoulder, of a shell having a projection adapted to engage said shoulder thereby to prevent longitudinal withdrawal of the shell from the cap, said projection being movable inwardly out of engagement with said shoulder, and releasable means for preventing inward movement of said projection.

2. In a socket casing, the combination with a cap having an inwardly concave circular bead adjacent its lower edge, of a shell having a projection adapted to engage in said bead thereby to prevent longitudinal withdrawal of the shell from the cap, said projection being movable inwardly out of engagement with said bead, and releasable

means for preventing inward movement of said projection.

3. In a socket casing, the combination with a cap having an internal shoulder, of a shell adapted to telescope, at its upper end, into said cap, a projection carried by said shell and adapted to engage said shoulder to prevent withdrawal of said shell, and a clamping screw carried by said shell and engaging said cap to clamp the latter against said shell so as to prevent angular movement of the shell relatively to the cap. 30

4. In a socket casing, the combination with a cap having an inwardly concave circular bead adjacent its lower edge, of a shell having a projection adapted to engage in said bead thereby to prevent longitudinal withdrawal of the shell from the cap, said projection being movable inwardly out of engagement with said bead, and releasable means for preventing inward movement of said projection, and also serving to prevent angular movement of said shell relatively to said cap. 40

5. In a socket casing, the combination with a cap having an internal shoulder, of a shell, a projection carried by said shell

and adapted to engage said shoulder, and a screw for locking said projection in engagement with said shoulder to prevent withdrawal of said shell, said screw also serving to clamp said cap to said shell so as to prevent angular movement of said shell relatively to said cap. 35

6. In a socket casing, the combination with a cap, of a shell telescopically engaging said cap, snap fastening means connecting the cap and shell, and means for positively holding said fastening means in engaged position. 40

7. In a socket casing, the combination with a cap, of a tubular shell telescopically engaging said cap, means movable inwardly and outwardly with respect to said shell for detachably connecting the cap and shell, and means for positively holding said connecting means in connecting position. 45

In witness whereof, I have hereunto subscribed my name in the presence of two witnesses.
